SANDAL OR SIMILAR ARTICLE

George S. Laham, Wichita, Kans.

Application April 30, 1954, Serial No. 30,265

Term of patent 14 years

(Cl. D7—7)

FIG. 1.

To all whom it may concern:

Be it known that I, George S. Laham, a citizen of the United States and a resident of the city of Wichita, in the county of Sedgwick and State of Kansas, have invented a new, original, and ornamental Design for a Sandal or Similar Article, of which the following is a specification, reference being had to the accompanying drawing, forming a part thereof.

On the drawing:

Figure 1 is a front perspective view of the sandal or similar article showing my new design; and

I claim:

The ornamental design for a sandal or similar article, as shown and described.
